CLAIM

The ornamental design for an energy module, as shown and described.

DESCRIPTION

FIG. 1 is a perspective view of an energy module. FIG. 2 is a front elevation view of the energy module of FIG. 1. FIG. 3 is a rear elevation view of the energy module of FIG. 1. FIG. 4 is a left elevation view of the energy module of FIG. 1. FIG. 5 is a right elevation view of the energy module of FIG. 1. FIG. 6 is a top plan view of the energy module of FIG. 1. FIG. 7 is a bottom plan view of the energy module of FIG. 1. FIG. 8 is a perspective view of an energy module. FIG. 9 is a front elevation view of the energy module of FIG. 8. FIG. 10 is a rear elevation view of the energy module of FIG. 8. FIG. 11 is a left elevation view of the energy module of FIG. 8. FIG. 12 is a right elevation view of the energy module of FIG. 8.

FIG. 13 is a top plan view of the energy module of FIG. 8;
and,

FIG. 14 is a bottom plan view of the energy module of FIG.
8.

FIG. 15 is a detailed view of the energy module of FIG. 4.

FIG. 16 is a detailed view of the energy module of FIG. 5.

FIG. 17 is a detailed view of the energy module of FIG. 11;
and,

FIG. 18 is a detailed view of the energy module of FIG. 12.

The wire frame lines shown throughout the views are
intended to indicate surface contour.

The broken lines in the drawings are for the purpose of
illustrating portions of the energy module that form no part
of the claimed design.

The dot-dash broken lines define the boundaries of the
detailed views shown in FIGS. 4, 5, 11, and 12, and form no
part of the claimed design.
